(57) **CLAIM**

The ornamental design for a rear portion for an automobile as shown and described.

DESCRIPTION

FIG. 1 is a front perspective view of a rear portion for an automobile showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is an enlarged portion of the rear perspective view thereof; and,

FIG. 9 is an enlarged portion of the right side view thereof. The ghosted or low contrasted showing of the motor vehicle is provided for the purposes of illustrating environmental structure and forms no part of the claimed design.

1 Claim, 9 Drawing Sheets
